Elizabeth A. Conklin

(57) **CLAIM**

The ornamental design for a cap for oral care composition container as shown and described.

DESCRIPTION

FIG. 1 is a perspective view of a first embodiment of a cap for oral care composition container, embodying the new design;

FIG. 2 is a top view thereof;

FIG. 3 is bottom view thereof;

FIG. 4 is left side view thereof;

FIG. 5 is a right side view thereof;

FIG. 6 is a front view thereof;

FIG. 7 is a back view thereof;

FIG. 8 is a perspective view of a second embodiment of a cap for oral care composition container, embodying the new design;

FIG. 9 is a top view thereof;

FIG. 10 is a bottom view thereof;

FIG. 11 is a left side view thereof;

FIG. 12 is a right side view thereof;

FIG. 13 is a front view thereof; and,

FIG. 14 is a back view thereof.

In the drawings, the evenly-spaced broken lines depict portions of the cap for oral care composition container that

(Continued)

form no part of the claim. The dot-dash broken lines represent the boundaries of the claim and form no part thereof.

1 Claim, 4 Drawing Sheets
